UNITED STATES PATENT OFFICE.

JAMES CLAYTON, OF BLACKPOOL, ENGLAND.

VALVE.

Application filed June 3, 1920. Serial No. 386,354.

To all whom it may concern:

Be it known that I, JAMES CLAYTON, subject of the King of Great Britain and Ireland, and resident of Blackpool, in the county of Lancaster, England, have invented certain new and useful Improvements in Valves (for which I have applied for a patent in Great Britain on May 28, 1919, Patent No. 154,948), of which the following 10 is a specification.

My invention relates to improvements in that class of valve having two separate cylindrical bodies within the main casing on a centre line at right angles to the operating spindle to which the valve is geared and a concentric cross-sectional area of flow between the cylindrical bodies forming the valve and the valve casing, which bodies engage with one another, one being fixed 15 and provided with a seating and the other provided with a facing surface and movable through the agency of an operating spindle to determine the flow of the liquid or fluid, the object being to provide improved means 20 for operating a valve of this type; improved means of mounting the valve; means for allowing the internal parts to be examined and interchanged; means for permitting expansion of the valve, a removable 25 valve face and means for allowing same to seat "squarely" and for moving the face to a different part of the seat when required.

With the aforesaid objects in view my invention consists in the combination with 30 the valve casing of a stuffing box and gland surrounding the operating spindle and a collar on the inner end of said spindle co-operating with the stuffing box to form a tight joint round the spindle; the combination of the inner valve casing supporting 35 the valve proper with a removable cover adapted to allow the whole of the valve parts to be removed from the casing of the valve; the means for allowing the screwed 40 spindle for operating the valve to be removed from the valve casing in which it is located consisting in passing one end of the spindle through such casing and securing thereto a removable collar and a removable 45 covering cap attached to the casing; in means for allowing expansion and contraction of the valve parts consisting in locating a spring between the end of the collar on the spindle and the covering cap; in a 50 renewable valve face composed of a seat-

ing ring held in position against a face on the valve by a nut and screwed connection and clamping plate; in a renewable valve face comprising a partly spherical disc having a curved inner face to bear upon 55 a corresponding face on the valve body and a central screwed shank passing through the latter and secured by a nut and a washer having a convex face seating in a concave on the valve body, the whole arrangement 60 enabling the valve to accommodate itself to the seat; and means for circumferentially adjusting the face when required, consisting in forming the valve with bevel teeth on its rear face and using in conjunction therewith to operate in the extreme open position of the valve a bevel pinion operated by 65 a shaft passing to the outside of the main valve casing and a stuffing box for keeping the shaft liquid tight. 70

My invention will be fully described with reference to the accompanying drawings in which—

Fig. 1, is a longitudinal section of a valve constructed in accordance with my invention, 80

Fig. 2, transverse section of valve body, Figs. 3 and 4 similar views showing modification of the valve,

Fig. 5, similar view to Fig. 1, of a valve 85 with further modifications,

Fig. 6, transverse section of a valve showing modified means for operating it,

Fig. 7, section of a valve showing a further form of renewable valve face and 90 gear for operating the valve and

Fig. 8, partial section of valve showing a modified form of the renewable face and means for rotating it.

Similar reference characters are applied 95 to corresponding parts in all the views of the aforesaid drawings.

Referring to Figs. 1 and 3 *a* indicates a stationary casing, flanged at each end for connection to a line of piping or the like 100 while *b* is a valve movable within it, on a centre line at right angles to the operating spindle to which the valve is geared. Internally it is provided with a fixed casing *c*, the whole formed in one with the outer casing *a* 105 but leaving a passage *e* for the liquid or fluid. The inner casing *c* is bored out to receive the inner end of the valve *b*, a tight joint formed between the two parts by a stuffing box *f* and gland *g* at the forward end 110

of the inner casing *c*. The valve is supported by the long bearing formed by the co-acting parts.

In accordance with my invention and referring to Figs. 1 and 3, the valve *b* is slideable within the casing *c* by providing its boss *m* with a screw thread, a corresponding thread being formed upon the spindle *h*. The spindle carries a bevel wheel *n* in gear with a bevel pinion *o* carried by a spindle *p* having a collar *q* working in a recess *r* in the main casing *a*. Above or in continuation of the recess is a stuffing box *s* fitted with a gland *t* and bottom ring *u*. These parts keep the spindle *p* liquid or fluid tight whilst allowing it to be freely operated to move the valve *b* to or from its seat *c¹*. The latter is formed in this instance by a removable ring *v*. The valve is prevented from rotating by a narrow guide piece *w* engaging with a groove *x* in casing *c*. The valve is fitted with a renewable seating ring *y* to engage with the seat *c¹*.

The screw valve spindle is adapted to be removed from the casing *c* by carrying its end 2 through the casing and fitting it with a removable collar nut 3. This nut keeps the spindle in position axially whilst permitting it to rotate. The collar is enclosed 30 by a removable cap 4 fixed to the casing *c* by screws 5.

In Figs. 3 and 4 the casing *c* and all the main valve parts are carried by a removable cover 6 which forms the upper portion 35 of the main valve casing *a* to which it is secured removably by studs and nuts 7. The valve *b* is arranged and operated in a substantially similar manner to that in Figs. 1 and 2 except that in place of a stuffing box 40 the operating spindle *p* has a collar 8 which makes a working joint with a subsidiary cover 9 secured to cover 6 by studs and nuts 10. By removing the cover 9 the operating spindle can be removed when required 45 whilst on the other hand by removing the cover 6 the whole of the valve parts can be entirely taken away from the casing *a* and be replaced by others if necessary, or be examined and repaired.

50 11 is a hand hole through which parts of the valve may be examined whilst in position, this hole being adapted to be suitably closed by any approved cover, which is not shown.

55 In Fig. 5 the valve is also provided with a removable cover 6 as in Figs. 3 and 4 but is provided with a stuffing box and packing arrangement similar to that shown in Figs. 1 and 2. The chief modification however 60 in this design consists in the employment of a spring 12 located between the outer end of the collar nut 3 and a removable cap 4 which differs from the cap shown in Figs. 1 and 3 in that it is recessed to receive the 65 outer end of the spring 12. The portion 2

of the spindle *h* is somewhat longer than the partition 13 between the collar nut 3 and the bevel wheel *n* so as to allow the expansion of the valve taking place under heat and to follow up contraction of the valve 70 when it cools. This arrangement enables the valve to be easily operated.

In Fig. 6 I have shown improved means for moving the valve *b* backwards and forwards, this consisting in fixing a worm 75 wheel 12 on the spindle *h* with which gears a worm 13 carried by a shaft 14 mounted in bearings 15 in the removable cover 6. The shaft 14 is operated by a hand wheel 17. 16 is a removable cover secured to the cover 80 6 and located above the worm 13.

In Fig. 7 the renewable face *y* is in the form of a ring mounted upon the shank *y¹* and held in position by a plate *y¹¹* and nut *y¹¹¹*. In the same figure the bevel pinion *n* 85 is formed in one with the short shaft 2 which passes into a recess 18 formed in the casing *c* instead of passing entirely through as in the examples previously described. In Fig. 7 also I have shown holes 19 through 90 which lubricant can be passed to the chamber containing the bevel wheels and screw *h*, thereby enabling the whole of the moving parts to be lubricated.

Fig. 8 shows a still further form of renewable valve face which in this case consists of a partly-spherical disc 20 curved on its inner face at 21 to correspond to a similar face on the valve body *b*. The disc is secured to the latter by a short freely 100 fitting screwed stud 22 nut 23 and a washer 24 flat on one side and partly spherical on the other to fit a corresponding hollow face in the valve body. Thus when the valve is being forced to its seat it can freely accommodate itself to the latter and make a tight joint. Means are also shown in Fig. 8 for turning the valve disc 20 with the stud 22, when required, to allow it to seat at a different position. To this end the disc 110 110 is provided with bevel teeth 25 which engages with a bevel pinion 26 when the valve is open. The pinion is fixed on a shaft 27 passing through the removable valve casing 6, fitted at its outer end with a handwheel 115 28. A stuffing box and gland 29 is used to keep a tight joint about the spindle. By rotating the shaft 27 the valve can be moved circumferentially to the position required. The bevel teeth are out of engagement when 120 the valve is closed.

In some cases the gland *g* may be flanged and be adjusted by the ordinary screws and nuts. Again the main casing *a* may be fitted with a small removable cover at the 125 bottom to enable the valve and gland to be got at for examination or adjustment. And, when required a drain cock may be fitted at this point also to drain out the liquid or sediment from the valve casing. 130

What I claim and desire to secure by Letters Patent is: —

1. In a valve, a main casing provided with a passage and a valve seat, an internal casing arranged in the said passage against one side of the main casing and provided with a cylindrical bore in line with the valve seat, a valve for cooperating with the valve seat to close the passage, said valve having a screw threaded hole and a stem which is slidable in the said bore, a screw threaded spindle journaled in one end wall of the internal casing and engaging with the screw threaded hole in the valve, and means for revolving the said spindle to open and close the valve.
2. A valve as set forth in claim 1, and in which the means for revolving the valve spindle comprise a beveled toothed wheel secured on the said spindle, an operating spindle journaled in one side of the main casing, and a beveled toothed wheel secured on the said operating spindle and gearing into the aforesaid beveled toothed wheel.
3. In a valve, a valve casing, a valve, a removable screw threaded spindle for operating the valve, said spindle having an end portion which is journaled in the said casing, a removable collar secured on the said end portion of the spindle and normally retaining it in position, and a removable covering cap for the collar attached to the said casing.

4. The combination, with a valve as set forth in claim 3, of a spring arranged between the said collar and cap and operating to press the collar against the casing.

5. In a valve of the type described, a valve body, a renewable valve face comprising a partly spherical disc having a curved inner face to bear upon a corresponding face on the valve body and a central screwed shank passing through the latter and secured by a nut, and a washer having a convex face seating in a concave face on the valve body, the whole arrangement enabling the valve to accommodate itself to the seat.

6. In a valve of the type described, the combination, with a removable valve face as claimed in claim 5, of means for circumferentially adjusting the disc in the extreme open position of the valve consisting of bevel teeth on the rear face of the disc, a bevel pinion engaging with said bevel teeth, a shaft for operating the pinion passing to the outside of the main valve casing, and a stuffing box for keeping the shaft liquid tight.

In testimony whereof I have hereunto set my hand in the presence of two witnesses.

JAMES CLAYTON.
